VELOCIPED BRAKE.

No. 400,343.

Patented Mar. 26, 1889.

Fig. 1

Fig. 2.

A technical line drawing of a mechanical assembly. At the top, a vertical rod labeled 'B' is attached to a horizontal frame. A curved arm labeled 'D'' is hinged to the vertical rod at point 'd'. Another curved arm labeled 'D'' is hinged to the first at point 'd''. A third curved arm labeled 'D'' is hinged to the second at point 'd''. The bottom part of the assembly is labeled 'C' and 'R'. The drawing is annotated with 'Fig. 3.' in a cursive script.

UNITED STATES PATENT OFFICE.

THOMAS B. JEFFERY, OF RAVENSWOOD, ILLINOIS.

VELOCIPED-BRAKE.

SPECIFICATION forming part of Letters Patent No. 400,343, dated March 26, 1889.

Application filed June 14, 1888. Serial No. 277,036. (No model.)

To all whom it may concern:

Be it known that I, THOMAS B. JEFFERY, a citizen of the United States, residing at Chicago, county of Cook, and State of Illinois, 5 have invented certain new and useful Improvements in Velocipede-Brakes, which are fully set forth in the following specification, reference being had to the accompanying drawings, forming a part thereof.

10 In the drawings, Figure 1 is a side elevation of a bicycle-head and portion of the drive-wheel, showing my improved brake attached to the head, the position of the brake-shoe being out of contact with the wheel. Fig. 2 is a similar side elevation showing the same parts with the brake-shoe in contact with the wheel. Fig. 3 is a similar view showing a modified form of the brake-operating mechanism. Fig. 15 4 is a similar elevation showing another modified form of the brake-operating mechanism. Fig. 5 is a plan of the forms shown in Figs. 1 and 2. Fig. 6 is a plan of the form shown in Fig. 3. Fig. 7 is a plan showing a modified form of the brake-handle applied to the construction shown in Figs. 1 and 2. Fig. 8 is a detail elevation of a modification of the connection of the brake-shoe to its lever.

A is the drive-wheel.

B is the head.

30 C is the brake-shoe, which in the forms shown in Figs. 1 and 2 is the terminal of the lever C', which is pivoted to the head, and in forms shown in Figs. 3 and 4 is an independent piece pivoted to the lever C'.

35 I will first describe the forms shown in Figs. 1 and 2. The lever C is a bell-crank lever pivoted to the head, at the lower end thereof, immediately above the fork, being in that respect similar to the common form of 40 bicycle-brakes. At the upper end, instead of having the brake-lever engaging it, as in the customary form, it is connected at d' by the link D' to the link D, which is pivoted to the head at d. The sum of the lengths of these 45 two links D and D' should be slightly greater than the distance between their pivots d and d', respectively, when the brake is in closest contact with the wheel; but said sum should be sufficiently greater than said distance so that the pivot d¹⁰, which connects the two links, cannot be depressed below a straight line between the pivots d d'. In this

form the brake-handle is most conveniently located at or near the pivot d¹⁰, and that pivot may itself be produced laterally to form the handle. It is immaterial upon which of the links D D' the handle is secured; but it is illustrated as secured to the link D near the pivot d¹⁰. An obvious modification of this construction consists in forming the pivot 55 d as a rock-shaft, of which the link D then becomes a lever-arm, and in providing said rock-shaft with a second lever-arm, D², at a convenient position to serve as a handle. This construction is illustrated in Fig. 7. In 60 either construction the brake is operated by depressing the junction of the links D D', whether that is accomplished by rocking the rock-shaft pivot of the link D or directly depressing the pivot d¹⁰. 70

In the form shown in Fig. 3 the action is substantially the same, the position of the several pivots only being changed, the lever-arm D¹⁰ of the bell-crank lever D¹⁰ D¹¹ corresponding in function perfectly to the link D' 75 in Figs. 1 and 2. This form, however, is particularly adapted to be used with the ordinary form of horizontal brake-lever shown in Fig. 6, such brake-lever engaging the upper end of the arm D¹¹ in the same manner as in 80 the customary construction it engages the upper end of the direct brake, and by pushing that upper end outward depresses the brake. In this construction the sum of the lengths of the link D' and the arm D¹⁰ should be slightly 85 greater than the distance between the pivots d' and d, said pivots corresponding precisely to the similarly-lettered pivots in Figs. 1 and 2.

In the form shown in Fig. 4 a roller, E, is 90 substituted for the link D, and the form of the lever C is changed, so that the track e of the roller E upon the upper edge of said lever makes nearly a right angle with a line through the pivots d d¹⁰, and the sum of the 95 lengths of the radius of the roller E and the lever-arm D¹⁰ is very slightly greater than the distance from the pivot d¹⁰ to the track e when the brake-shoe is in closest contact with the wheel. It will be noticed that the action of 100 this form is substantially the same as that of the form shown in Figs. 3 and 4, and in all of these forms the purpose of the construction adopted is to reach the maximum effective-

ness of pressure applied to the brake-handle, for the purpose of producing pressure upon the wheel by means of the brake-shoe at the instant of contact of the brake-shoe and the 5 wheel, so that very slight pressure by the hand of the operator upon the handle will suffice to apply a powerful pressure to the wheel. In order to obtain this result, it will be noticed that it is necessary in all these 10 constructions to employ, besides the lever which carries the brake-shoe, an auxiliary lever pivoted on the head and in the same vertical plane, and communicating pressure to the brake-carrying lever by means of an 15 intermediate piece which is connected to or in contact with said lever, so that the distance traced from the pivot of the said auxiliary lever through the point of connection of said intermediate piece with said lever to its connection or contact with the brake-carrying 20 lever shall be slightly greater than the direct distance from the pivot of the auxiliary lever on the head to the contact of the intermediate piece with the brake-carrying lever when the 25 brake is on the wheel.

The brake-shoe in all these constructions may be either rigid with the lever C or pivoted to it. The advantage of pivoting it is that it may readily adjust itself to the wheel, 30 and thereby obtain more complete contact with it as it is pressed upon it; but in order that it may not have any tendency to dig its rear end into the rubber tire I prefer to interpose between it and the lever C the springs 35 $c' c^{10}$, one before and one behind its pivot. The spring c^{10} should either be stronger or farther from its pivot than the spring c' , in order that the tendency of the shoe shall be to press by its forward end, rather than its 40 rear end, upon the tire, but so that as pressure is applied sufficiently to cause the spring c^{10} to yield it may come down onto the tire throughout its entire length. The advantage of the rear spring, c' , is, that it permits the 45 shoe to be so hung that in its normal position throughout almost its entire length it shall contact with the tire when first brought into contact with it, and yet shall not be in danger of digging into it at the rear end. In- 50 stead of this spring, there may be employed a positive stop to check the action of the spring c^{10} at a position such that the desired amount of contact of the shoe with the tire may be obtained. Such a stop is illustrated 55 in Fig. 8, consisting of the protuberance c^{11} from the under side of the lever C.

I claim—

1. In a velocipede, in combination with the wheel and the head, the brake-carrying lever 60 pivoted to the head, and an auxiliary lever, also pivoted to the head, and an intermediate

piece pivoted to said auxiliary lever and actuating the brake-carrying lever, the distance from the pivot of the auxiliary lever to the contact of said intermediate piece with the 65 brake-carrying lever, when the brake-shoe is in closest contact with the wheel, being nearly equal to the sum of the distances from the pivot of said auxiliary lever on the head to the pivot to said lever of the intermediate 70 piece and the distance from the last-named pivot to the contact of the intermediate piece with the brake-carrying lever, substantially as and for the purpose set forth.

2. In combination with the wheel and the 75 head, the brake-carrying lever pivoted to the head, and an auxiliary lever, also pivoted to the head, and a link connecting said auxiliary lever to the brake-carrying lever, the sum of the lengths of said link and the auxiliary 80 lever being slightly greater than the distance between their pivots to said brake-carrying lever and head, respectively, when the brake-shoe is in contact with the wheel, substantially as and for the purpose set forth. 85

3. In a velocipede, in combination with the wheel and the head, the brake-carrying lever pivoted to the head, and an auxiliary lever, also pivoted to the head, the brake-carrying lever having an upwardly-extending arm, and 90 a link connected from said arm to the auxiliary lever, the sum of the lengths of said links and auxiliary lever being slightly greater than the distance from the pivot of the auxiliary lever on the head to the pivot of the link to 95 the brake-carrying lever when the brake-shoe is in contact with the wheel, substantially as and for the purpose set forth.

4. In a velocipede, in combination with the head and the wheel, the brake-carrying lever 100 pivoted to the head, and the brake-shoe pivoted to said lever, and a spring reacting between the shoe and the lever forward of the pivot of the shoe to force the shoe toward the wheel, and a stop to limit such movement of 105 the shoe about its pivot, substantially as and for the purpose set forth.

5. In a velocipede, in combination with the wheel and the head, the brake-carrying lever having the brake-shoe pivoted to it and provided with two springs, one in front and one 110 behind its pivot, reacting between it and the lever, substantially as and for the purpose set forth.

In testimony whereof I hereunto set my 115 hand, in the presence of two witnesses, at Chicago, this 11th day of June, 1888.

THOS. B. JEFFERY.
